UNITED STATES PATENT OFFICE

MAURICE B. RIPIN, OF NEW YORK, N. Y., ASSIGNOR TO UNITED STATES WOVEN LABEL COMPANY, OF NEW YORK, N. Y., A CORPORATION OF NEW YORK

FABRIC LABEL AND THE LIKE

Application filed April 16, 1931. Serial No. 530,484.

This invention relates to textile fabric labels and the process by which the same are made. It also has reference to any other article of manufacture that may be composed 5 of a woven, knitted or other textile fabric, wherein it is desired to produce a plurality of panels or fabric sections from a single fabric piece by cutting the same therefrom, this act of severing or separating such panels 10 or pieces serving to provide each of the same with one or more finished edges, or edges which will not fray when put to normal use.

At the present time, woven fabric labels are generally produced in the form of a continuous fabric strip, the labels comprising 15 said strip being severed therefrom. Labels cut from the strip in this manner are thus formed with two "raw" or cut edges which tend to fray or unravel readily. It is therefore necessary, when attaching such labels to a garment or other article to turn in and hem or otherwise reinforce these cut edges 20 to prevent this fraying or unraveling tendency and to generally improve the appearance 25 of the attached label.

The advantages of my improved construction will be apparent when consideration is given to the fact that a great deal of time and labor is consumed in inturning and 30 hemming the raw or cut edges of the labels ordinarily provided, either before said labels are attached to the garments or while such attachment is taking place. Similarly, many other cut fabric articles must, after 35 being cut from a fabric section, be inturned and hemmed or else have their cut edges otherwise reinforced by binding, overstitching or the like to prevent such edges from fraying.

40 The object of this invention, therefore, is to provide a section, strip or piece of fabric that is divided into a plurality of lesser pieces such as labels, panels or the like, with each of said labels, panels or the like having at 45 least one of their edges while in the piece, defined by an inturning of the fabric or by a reinforcement of stitching, weaving or knitting, so that, when severance of the piece adjacent to the inturned edge or line occurs, 50 a "finished" edge defined by said inturning

or normally non-fraying line, results. Thus, when the labels or other articles are cut from the strip or section of which they initially formed a part, they have finished or hemmed edges, and can be speedily attached to a 55 garment or the like with a minimum of time and effort.

I have, in describing my invention hereafter, referred specifically to its applicability to woven label manufacture. This, however, 60 is merely illustrative, as its applicability to the textile art generally whenever separately defined panels are to be separated from a fabric piece, section or strip by a cutting operation, will be readily discerned by those 65 skilled in the art to which this particular invention belongs.

With the objects heretofore stated, in view, I have devised the particular arrangement of 70 parts hereafter described and more particularly pointed out in the claims appended hereto.

Reference is to be had to the accompanying drawings, forming a part hereof in which

Figure 1 is a perspective view of a fabric 75 strip composed of a series of integrally connected panels or labels, said strip illustrating one embodiment of my invention;

Figure 2 is a perspective view of the rear face of a part of the strip disclosed in Fig- 80 ure 1;

Figure 3 is a front view of a label that has been cut from the strip shown in Figures 1 and 2;

Figure 4 is a perspective view of a modified construction;

Figure 5 is a rear view, in perspective, of the strip shown in Figure 4; and

Figure 6 is a perspective view of a label severed from the strip disclosed in Figures 4 85 and 5.

Throughout the various views of the drawings, similar reference characters designate similar parts.

In the embodiment of my invention disclosed in Figures 1 and 2, 1 indicates the body of a woven fabric strip. In referring to this section of fabric as a "strip" it will be understood that the same may be a large or 95 small fabric section or piece and need not 100

necessarily be of the narrow, elongated form disclosed, but may well be of entirely different proportions to suit the shape of the particular articles formed as a part of said strip 5 and adapted to be subsequently severed therefrom. Also, in referring to said strip or fabric piece as being of "woven" textile fabric, I do not wish to be understood as limiting my invention thereby, since under certain conditions, the fabric section or strip 10 may well be of flat or circular knitted character or of other construction.

In the illustrative embodiment shown, the strip 1 is of elongated character and is intended for the production of fabric labels. Said strip has two opposite longitudinal side edges 2 and 3 which are, in the manufacture of said strip, woven or otherwise produced with the usual selvage, so that these two edges 15 are of "finished" or non-fraying character.

The strip is sectionally divided into a series of integral label panels 4, which are intended to be severed from said strip when desired and attached to garments or other articles of wearing apparel. Between each two labels I provide two spaced loops, tucks or gathers 20 5 and 6, which loops, tucks or gathers serve to define in the strip, and later form the opposite longitudinal edges of, each label. These loop elements 5 and 6 extend from one of the selvaged edges 2 to the opposite selvaged edge 3 and may be formed in numerous ways, the formation thereof being dependent upon the manner in which the fabric strip is woven 25 or otherwise produced. In the structures disclosed in the drawings, I have shown these loops or tucks formed by doubling back the warp threads of the strip and causing an engagement of said warp threads, indicated at 30 7, with the weft, and then continuing the ordinary weaving of the strip until the point where the next loop is to be formed is reached, whereupon the process is repeated. It is also 35 entirely feasible to weave the strip in flat form and then produce these loops by a gathering or tucking attachment of a sewing machine. It is also possible to form said loops by folding the fabric body and maintaining the loops by adhesively uniting the 40 folds.

These methods and other methods of forming the loops or tucks in the strip will be readily apparent to the skilled weaver or sewing machine operator.

It will be seen that the loops or tucks 5 and 6 in each pair, are spaced a slight distance apart, thus providing a narrow strip or fabric area between them, such area being indicated by the reference numeral 8. Said area 45 8 provides a space for cutting the labels apart, the lines of severance of said labels being indicated at 9.

By reference to Figure 3, the construction of a label severed from the strip of Figures 65 1 and 2, will be apparent. It will be seen that

the mere act of severing one of the labels from the strip 1 serves to provide a label that is furnished on all of its four edges with a finished edge reinforcement. That is, two of its edges have the customary selvage, at 2 and 3, and 70 its other two edges are provided with in-turned or hemmed reinforcements, these reinforcements being formed by the loops or tucks 5 and 6 that are produced while the labels are integrally connected together in strip form 1. From the description just given, it will be seen that I provide a strip or fabric piece that is composed of connected label panels, each of which panels is provided while in the strip with the pre-formed finished edges, whereby a subsequent inturning or formation of such edges on the cut labels is entirely dispensed with.

In Figures 4 to 6 inclusive, a modified structure is disclosed, wherein the finished cut label, as shown in Figure 6, is provided with three finished edges, rather than with four as was described with reference to the structure disclosed in Figures 1 to 3 inclusive.

The strip disclosed in Figures 4 and 5 is 85 similar in general construction to that of Figure 1, except that instead of being provided with the loops or tucks in groups of two, single loops or tucks are formed at spaced intervals across the strip, which loops extend from one of the selvaged edges to the other. Each of said loops 10 defines and later forms, one edge as at 11, of one of the labels 12 that comprise the strip and are subsequently cut therefrom. The strip disclosed in Figures 4 and 5 90 may, of course, be made in any of the ways heretofore described with respect to the structure of Figures 1 and 2, the sole difference being with respect to the number of loops formed.

To sever the labels 12 from the strip of Figure 4, cuts are made along the lines 14, the resultant cut label being shown in Figure 6. It will be there seen that said label is provided with three finished edges, that is, the edges 2, 3 and 11. The edge 13, being the cut edge, is a "raw" or unfinished edge which is generally inserted between layers or parts of the garment or article of wearing apparel to which it is to be attached, and this unfinished 100 edge is thus concealed from view.

While I have specifically disclosed my invention as being applied to the manufacture of labels from a fabric strip, it will be understood that this is merely illustrative of one of the embodiments of my invention, as the same may well be applied to the manufacture of other fabric articles, sections, pieces or the like wherein the preformation of finished edges on such articles, sections or pieces before the severance of the same from a larger section is desirable or necessary.

While I have herein described the edge reinforcements of the labels as "loops", "tucks", "hems", "folds" and the like, and have shown 110

such reinforcements of considerable size for the purpose of illustration, it will be understood by those skilled in the art, that these reinforcements may be made in many ways and 5 may be minute in character, yet be capable of successfully performing the function intended, i. e., if providing finished or reinforced edges and avoiding the fraying tendency of the ordinary unreinforced cut edge.

10 Having described several embodiments of my invention, it is obvious that the same is not to be restricted thereto, but is broad enough to cover all structures coming within the scope of the annexed claims.

15 What I claim is:—

1. A fabric strip divided into a plurality of panels intended for separable use, said strip being provided with a plurality of spaced loops, each of said loops forming an inturned edge on a panel when said panel is severed 20 from the strip.

2. A fabric strip divided into a plurality of panels intended for separable use, said strip being provided with a plurality of spaced 25 loops extending from one edge of the strip to its opposite edge, said loops being arranged in pairs, said strip being adapted to be severed between each pair of loops to divide the strip into panels whose opposite 30 edges are formed by loops.

3. A fabric strip composed of a plurality of integrally joined labels, one of the edges of each of said labels being inturned while said labels are connected together in the strip.

35 4. A fabric strip composed of a plurality of integrally joined labels, two of the edges of each of said labels being inturned while said labels are connected together in the strip.

5. A fabric strip composed of a plurality of 40 integrally joined labels, said strip being provided with selvaged longitudinal edges, said strip having one of the edges of each of said labels defined by a loop formed in the strip and extending across the same and connecting 45 the selvaged edges thereon.

6. A textile fabric piece divided into a plurality of lesser sections adapted to be cut from said piece, each of said sections having at least one of its edges defined by a tuck 50 formed in the piece, which tuck subsequently forms an inturned edge on said lesser section when the same is cut from the piece on a line adjacent to said tuck.

7. A textile fabric piece divided into a 55 plurality of lesser sections adapted to be cut from the piece, said piece being provided with spaced tucks formed in it to define the opposite edges of said lesser sections and to form opposite inturned edges thereon when 60 said sections are subsequently severed from the piece.

8. A strip of connected fabric labels, each 65 two labels in said strip having a spaced pair of tucks located between them.

9. A strip of connected fabric labels, the

strip having a tuck formed in it between each two labels.

10. A textile fabric piece divided into a plurality of lesser sections adapted to be cut 70 from the piece, each of said sections being separated from that adjacent to it by fray-limiting means formed while said sections are in the piece.

11. A textile fabric piece divided into a plurality of lesser sections adapted to be cut 75 from the piece, each of said sections being separated from that adjacent to it by fray-limiting means provided while said sections are in the piece, said fray-limiting means extending along spaced lines with an area provided between them within which the sections are severed from one another.

12. The process of manufacturing fabric 80 labels consisting in producing a fabric strip composed of a plurality of integrally joined labels and in producing an inturned edge on each of the labels during the formation of said strip.

13. The process of manufacturing labels 85 consisting in producing a fabric strip composed of a plurality of labels and in producing a pair of opposite inturned edges on each label during the formation of the strip and prior to the separation of the labels therefrom.

14. The process of manufacturing fabric 90 panels consisting in producing a plurality of connected panels in the form of a single fabric sheet, in providing tucks in the sheet to separate said panels, and in severing the sheet on lines adjacent to said tucks whereby said tucks form at least one inturned edge on each of said cut fabric panels.

15. The process of manufacturing fabric 95 labels consisting in producing a strip containing a plurality of integrally connected labels, in providing said strip with longitudinally selvaged edges, in forming folds in the strip between the labels, and in severing the labels from the strip by cuts made adjacent to the folds therein.

16. A fabric panel having a hemmed edge, the hem thereon being maintained by threads forming a part of the body of the panel.

Signed at the city, county and State of New 100 York, this 15th day of April, 1931.
